(57) CLAIM

The ornamental appearance of a headgear, as shown and described.

DESCRIPTION

FIG. 1 is a perspective view of headgear for use with a respiratory mask assembly according to my design;
FIG. 2 is a front view thereof;
FIG. 3 is a rear view thereof; and,
FIG. 4 is a bottom view thereof.

The headgear shown in the figures is shown in its pre-use condition. The headgear is designed to wrap about the head of a patient in use.

The broken lines indicate environmental structure and are for illustrative purposes only and form no part of the claimed design.
